[57] CLAIM

The ornamental design for a sprayer, substantially as shown and described.

DESCRIPTION

FIG. 1 is a front perspective view of the sprayer showing my new design;

FIG. 2 is a rear perspective view thereof;

FIG. 3 is a top plan view thereof; and

FIG. 4 is a front elevation thereof.

The broken-line showing of a container, tubing nozzle, and straps in FIG. 1 is for illustrative purposes only and forms no part of the claim design.

Fig. 5.

Fig. 4.
